US00D986927S

(12) **United States Design Patent** (10) **Patent No.:** **US D986,927 S**
(45) **Date of Patent:** **** May 23, 2023**

(54) **PUMP HOUSING FOR PNEUMATIC
COMPRESSION DEVICE**

(71) Applicant: **Therabody, Inc.**, Los Angeles, CA
(US)

(72) Inventors: **Jaime Sanchez Solana**, Los Angeles, CA (US); **Brian Carberry**, Beverly Hills, CA (US); **Brian Zeng**, Dongguan (CN); **Washington Alexander Silva Garces**, Los Angeles, CA (US); **William Webb**, San Francisco, CA (US); **Patrick Tufts**, San Francisco, CA (US); **Cale Kaufman**, Oakland, CA (US)

(73) Assignee: **Therabody, Inc.**, Los Angeles, CA (US)

(**) Term: **15 Years**

(21) Appl. No.: **29/868,261**

(22) Filed: **Nov. 28, 2022**

Related U.S. Application Data

(62) Division of application No. 29/821,804, filed on Jan. 3, 2022, now Pat. No. Des. 971,266.

(57) **CLAIM**

The ornamental design for a pump housing for pneumatic compression device, as shown and described.

DESCRIPTION

FIG. 1 is a top perspective view of a pump housing for pneumatic compression device showing the claimed design; FIG. 2 is a front elevational view thereof; FIG. 3 is a rear elevational view thereof; FIG. 4 is a right elevational view thereof; FIG. 5 is a left elevational view thereof; FIG. 6 is a top plan view thereof; and, FIG. 7 is a bottom plan view thereof.

1 Claim, 6 Drawing Sheets
